UNITED STATES PATENT OFFICE.

CHARLES M. DRENNAN, OF BOSTON, MASSACHUSETTS.

DESIGN FOR A CASKET-COVER.

SPECIFICATION forming part of Design No. 30,965, dated June 6, 1899.

Application filed May 10, 1899. Serial No. 716,291. Term of patent 14 years.

To all whom it may concern:

Be it known that I, CHARLES M. DRENNAN, a citizen of the United States, residing at Boston, county of Suffolk, and Commonwealth of Massachusetts, have invented and produced a new and original Design for a Casket-Cover, of which the following is a specification.

Figure 1 is a perspective view of a casket-cover, illustrating my design, the view being directed toward the top of the casket-cover; and Fig. 2 is a section on the line *x*, Fig. 1.

The leading feature of my design for a casket-cover consists, essentially, of an elongated body having a central depression, the sides of which are upwardly directed and then curved downwardly in two separate curves.

The casket-cover comprises an elongated body *A*, having a central depression *a*, the edges *a'* of which rise therefrom, said edges being prolonged by two curved bodies *b* and *c*. ²⁰

Having fully described my design, what I claim, and desire to secure by Letters Patent, is—

The design for lid of casket, substantially as herein shown and described.

In testimony whereof I have signed my name to this specification in the presence of two subscribing witnesses.

CHARLES M. DRENNAN.
